UNITED STATES PATENT OFFICE.

FERDINAND LAHM, OF ST. LOUIS, MISSOURI.

DESIGN FOR A BUTTON.

SPECIFICATION forming part of Design No. 22,381, dated May 2, 1893.

Application filed March 2, 1893. Serial No. 464,454. Term of patent 14 years.

To all whom it may concern:

Be it known that I, FERDINAND LAHM, of the city of St. Louis and State of Missouri, have invented a certain new Design for Buttons and Charms, of which the following is a full, clear, and exact description, reference being had to the accompanying drawings, forming a part hereof.

Referring to the drawings: Figure 1 is a detail plan view. Fig. 2 is a transverse section taken through the same.

The design is circular in contour and is provided with a marginal rim 1 having its front surface configured to represent a tape-measure.

2 indicates a body configured to represent shears in an open position, the handles of which are located at the top of the design and resting upon the outer surface of the rim 1, and the blades of which are similarly located at the lower portion of the design.

3 indicates a body configured to represent a tailor's square. The extremities of said body 3 are located beneath the rim 1 and sub-

stantially in a plane above a horizontal line 25 drawn through the center of the circle represented by said rim 1, and the angle of said square is located between the two portions of the body which represent the blades of the shears, with the arms of the same resting 30 upon the representation of said blades.

4 indicates a body configured to represent a sad-iron, the body of which is located in the rear of the body representing the shears and extends horizontally from arm to arm of the 35 body representing the square, the handle of said sad-iron being represented as crossing the handles of said shears in front of same.

What I claim is—

The design for a button as herein shown 40 and described.

In testimony whereof I affix my signature in presence of two witnesses.

FERDINAND LAHM.

Witnesses:

ALFRED A. EICKS,
HERBERT S. ROBINSON.
